UNITED STATES PATENT OFFICE.

GEORGE M. SMITH, OF MARYVILLE, TENNESSEE, ASSIGNOR OF ONE-FOURTH TO
RUTHERFORD M. HENRY, OF MARYVILLE, TENNESSEE.

GRATE.

Application filed March 16, 1922. Serial No. 544,203.

To all whom it may concern:

Be it known that I, GEORGE M. SMITH, a citizen of United States, residing at Maryville, in the county of Blount, State 5 of Tennessee, have invented certain new and useful Improvements in Grates; and I do hereby declare the following to be a full, clear, and exact description of the invention, such as will enable others skilled in the art 10 to which it appertains to make and use the same.

This invention relates to new and useful improvements in grates and particularly to grates for fire-places.

15 One object of the invention is to provide a grate basket which is formed of two parts which may be quickly and easily separated.

Another object of the invention is to provide a grate basket of this character which 20 is capable of attachment to the ordinary grate frame of a fire-place and in which the grate bar member may be quickly and easily removed so that it may be replaced by a new one.

25 Another object of the invention is to provide a grate having a removable grate bar section which is adapted to be quickly and easily slipped forwardly to dump the ashes and cinders therefrom.

30 Ordinarily the grate bar portion of a grate basket is the portion which burns out or rusts out and seldom lasts more than a couple of years. The commonly constructed grate has the bars formed integrally with the front

35 part of the basket so that when the grate bars burn out it becomes necessary to renew the entire grate basket at considerable expense. With the present construction this is obviated, as only that which is subjected 40 to the greatest wear is readily renewable.

Other objects and advantages will be apparent from the following description when taken in connection with the accompanying drawing.

45 In the drawing:

Figure 1 is a front elevation of a grate basket made in accordance with the invention.

Figure 2 is a side elevation of the same.

50 Figure 3 is a vertical sectional view on the line 3—3 of Figure 1.

Figure 4 is a perspective view of the re-

movable grate member, removed from the front member.

Referring particularly to the accompanying drawing the front member of the grate basket comprises the vertical end bars 10, which are connected by the longitudinal bars 11, and between these bars 11 extend the vertical spaced bars 12. All of these parts, as 55 will be readily understood are cast in one piece of metal. The lower ends of the side bars 10 extend downwardly below the lower bar 11, to form the legs 13, and each of these legs has a laterally and inwardly directed 60 vertical ledge portion 14.

The grate member comprises the side bars 15, which are connected at their forward ends by the bar 16, and at their rear ends by the bar 17, said bars being cast in a single 70 piece. The forward end of each of the side bars 15 is turned upwardly as shown at 18, while the rear ends of the bars 15 have downwardly turned portions 19. Formed on the lower face of each of the side bars 15, a short distance inwardly from the forward end thereof, and projecting downwardly, is the lug 20, the forward end of which has the straight shoulder 21. The rear face of each of the bars 10 is formed with rearwardly and downwardly extending lugs 22, adapted to engage with the ordinary lugs of a fire-place not shown, but of well known type. Extending from the front to the rear of the 75 grate member are the parallel spaced grate bars 24.

It will be noted that the distance between the upper face of the projection 14 and the lower face of the downwardly extending projection 11' of the lower horizontal bar 11 is less than the vertical dimension of the forward portion of the side bar 15, inwardly of the portion 18 whereby, when the grate member is lifted vertically the nose of the lug 20 rises above the upper face of the portion 14 so that the grate member may be readily slipped forwardly and completely removed from the front member of the basket. When properly assembled, the forward portion of the members 15 rest on the 80 projections 14 with the upwardly extending portions 18 bearing against the front of the basket, while the shoulder 21 bears against 85 the rear vertical face of the projection 14.

Thus the grate member is properly supported on the front member of the basket. The bars 16 and 17 so space the members 15 that lateral movement of the grate member 5 from the projections 14 is prevented.

The weight of the rear end of the grate member serves to maintain the portion 18 and lug 20 to properly engage with the front of the basket. By this construction when 10 the grate member is burned out, or should become broken, that portion may be quickly and easily removed by simply lifting the grate member to a sufficient height for the lugs 20 to clear the projections 14. The new 15 grate member is then slipped into place as before described.

When it is desired to dump the cinders and ashes from the grate, the grate bar member 15 is pulled forwardly through the 20 front member until the lugs 19 engage the members 14. The grate bar member can then be readily pushed back into place.

What is claimed is.

1. A grate basket comprising a front 25 member having legs, said legs having ledges, and a removable grate member comprising a frame resting on said ledges, said frame having lugs bearing against the front face of

the front member of the basket and lugs bearing against the rear of the ledges, said 30 grate member being removable through the front member.

2. A grate basket including a front wall having a downwardly extending pair of L-shaped legs with the horizontal ledge portions thereof directed inwardly toward each other, and a grate member comprising a frame including front, rear, and side bars and connecting grate bars, the side bars resting on said ledge portions, said grate member being removable through the front of the basket and arranged to extend horizontally 35 inward from the front of the basket, each of the side bars having its forward end upturned to bear against the front of the 40 basket and a downwardly extending lug arranged to bear against the rear of the said ledge portions to maintain the grate member in a horizontal position.

In testimony whereof, I affix my signature, 45 in the presence of two witnesses.

GEORGE M. SMITH.
